UNITED STATES PATENT OFFICE

153,271

DESIGN FOR A VACUUM CLEANER
OR THE LIKE

Carl Oskar Ernolf, St. Essingen, Stockholm, Sweden, assignor to Electrolux Corporation, Old Greenwich, Conn., a corporation of Delaware

Application June 11, 1948, Serial No. 146,910
In Sweden December 13, 1947

Term of patent 14 years

(Cl. D9—2)

To all whom it may concern:

Be it known, that I, Carl Oskar Ernolf, a subject of the King of Sweden and a resident of St. Essingen, Stockholm, Sweden, have invented a new, original, and ornamental Design for a Vacuum Cleaner or the Like, of which the following is a specification, reference being had to the accompanying drawings, forming a part thereof and of which:

Fig. 1 is a side view of a vacuum cleaner or the like showing my new design;

Fig. 2 is a front view of the vacuum cleaner shown in Fig. 1;

Fig. 3 is a rear view of the vacuum cleaner shown in Fig. 1; and

Fig. 4 is a perspective view of the vacuum cleaner shown in the preceding figures.

I claim:

The ornamental design for a vacuum cleaner or the like, as shown,

CARL OSKAR ERNOLF.
